TOY CARTRIDGE

Arthur W. Lifquist, Los Angeles, Calif.

Application November 13, 1950, Serial No. 195,330

3 Claims. (Cl. 102—39)

1

This invention relates to a cartridge and more particularly to a toy cartridge adapted to be used in a toy pistol, rifle, cannon or similar devices, and is further adapted to receive an explosive cap for explosion therein.

The desire of children to play with toy firearms is ever increasing, thus producing the associated necessity for the production of such toys in a manner closely resembling actual firearms. While it is desirable from a sales standpoint to produce as near exact replicas of these devices as possible, consideration must also be given to the safety of the user as well as to others, inasmuch as explosive devices, unless properly handled, can cause serious injury.

Another problem arising from the production of replica firearms and cartridges is that of producing devices that may only be used as toys with little or no possibility for use as a means of destruction.

Therefore, it is the main object of the present invention to provide a novel toy cartridge for use in a toy firearm.

Another object of the invention is to provide a novel toy cartridge that is safe for use by children.

Another object of the invention is to provide a toy cartridge that may be easily loaded and handled by children.

A further object of the invention is to provide a novel toy cartridge that is inexpensive in manufacture, simple in design, yet effective in use.

Other and further important objects of the present invention will become apparent from the disclosures in the following specification, appended claims and accompanying drawings wherein:

Fig. 1 is a side elevational view of the toy cartridge of the present invention;

Fig. 2 is a right end view of the cartridge shown in Fig. 1;

Fig. 3 is a longitudinal sectional view taken substantially as indicated by line 3—3 of Fig. 1;

Fig. 4 is a transverse sectional view, partially in elevation, taken substantially as indicated by line 4—4 of Fig. 3;

Fig. 5 is a sectional view, partially in elevation similar to Fig. 3 showing a modification of the invention;

Fig. 6 is a transverse sectional view taken substantially as indicated by line 6—6 of Fig. 5 and showing a modified form of strike member; and

Fig. 7 is a view similar to Fig. 5 showing a further modification of the invention.

Referring to the drawing, which is for illustrative purposes only, by reference characters,

2

the invention as embodied in a toy cartridge is indicated generally at 10 (see Figs. 1 to 4). The cartridge includes an outer, substantially tubular shaped, elongated body portion 11, having its forward end tapered inwardly as at 12 and being provided with an opening 13 at the forward end thereof. The rearward end of the body portion 11 is threaded as at 14 to thereby receive threads 15 on a closure member 16.

The closure member 16 is provided with an outwardly extended flange portion 17 having a diameter greater than that of the body portion 11 to thus provide a rear shoulder for the cartridge when the closure 16 is in place. This shoulder 15 helps to retain the cartridge in position in a firearm. The closure 16 is also provided with an axial bore 18 in which a firing pin 19 is slidably positioned and which is adapted to extend beyond the inner end 20 of the closure 16 and into the central area of the body portion 11. The firing pin 19 is also provided with a hammer portion 21 on the inner end thereof. A compression spring 22 is arranged about the inner end of the firing pin 19, one end being in engagement with the hammer portion 21 and the other end engaging the inner surface 20 of the closure 16. The outer end of the firing pin 19 is provided with a head portion 23 which may be formed thereon after assembly of the firing pin 19, spring 22 and closure 16, to thus retain the pin 19 in place.

An anvil member 24 is arranged transversely of the interior of the body portion 11 and is adapted to fit securely in a bore 25 in the wall of the body portion 11. The anvil member may be substantially circular in cross section and has a flat portion 26 thereon which provides a surface upon which an explosive cap C similar to those commonly used in toy pistols, may be placed.

In use, the cartridge of the present invention 40 may easily be loaded for use in a toy pistol or similar toy firearm by the most inexperienced children. While holding the portion 11 of the cartridge, the flange 17 of the closure 16 may be grasped and turned to thus remove the closure 45 from the body portion. An explosive cap C is then inserted into the now open rearward end of the body portion 11 and allowed to rest on the flat area 26 of the anvil 24. The closure 16 is then replaced and, as seen in Fig. 3, the spring 50 22 engaging the hammer 21 of the firing pin will retain the cap C in position. The cartridge may then be loaded into the cylinder of a pistol or the breech of a rifle to thereby be in a position wherein the head portion 23 of the firing pin 19 55 may be struck by any suitable mechanism within

the firearm, an operation usually initiated by pulling a trigger.

Thus it may be seen that a new and different type of toy cartridge for use in toy firearms has been invented. It is to be noted that the space provided about the anvil 24 within the body portion 11 will allow the flame and smoke usually accompanying the explosion of a cap to pass forwardly and through the opening 13 in the body portion, thence to be dissipated before leaving the end of the gun barrel and thereby away from the individual firing the gun. This operation is contrary to the usual case where a cap is inserted in the back portion of a toy gun and the flame, smoke and bits of flying paper allowed to be blown laterally with possible injury to the user.

Referring now primarily to the modification shown in Figs. 5 and 6 wherein like parts are indicated by single prime reference numerals, the firing pin 19' with its associated head portion 23' has a hammer portion 30 and an associated inwardly directed tubular portion 31. The tubular portion 31 is adapted to be secured as by a force fit or welding on the end 32 of the firing pin 19' to thus provide a shoulder 33 which may abut the inner surface 20' of the closure 16'. In this modification the firing pin 19' may slidably float within the axial bore 18' to be retained therein by the tubular portion 31 and the head portion 23'.

This modification is also provided with an anvil 34 which may be formed integrally with the body portion 11'. The anvil member 34 has an enlarged, circular shape, centrally positioned, substantially flat striking surface 35, as seen in Fig. 6.

In use the modification shown in Figs. 5 and 6 is loaded in substantially the same manner as the cartridge of Figs. 1 to 4. In this modification it is necessary that the explosive cap C' be made sufficiently large in diameter to fit snugly within the body portion 11' while resting against the anvil 34, to thus be retained therein.

In Fig. 7 a further modification is shown wherein like parts are indicated by double prime reference numerals. In this modification the closure member 40 is adapted to be pressed into a taper 41 in the body portion 11" to thus be retained therein. The firing pin 19" may slidably float within an axial bore 18" in the closure 40 to be retained therein by the hammer portion 21" and the head portion 23". An anvil 34" may be similar to that used in the modification of Figs. 5 and 6.

In this modification loading and use of the cartridge is similar to that formerly described with the exception that the closure 40 is merely pulled to effect a release from the body portion 11" and replaced by pressing into position.

Having thus described the invention and the present preferred embodiments thereof, it is desired to emphasize the fact that many modifications may be resorted to in a manner limited only by a just interpretation of the following claims.

I claim:

1. A toy cartridge comprising: an elongated

tubular body, a reduced diameter portion at an end of said body; an anvil associated with and extending through said body, said anvil formed to occlude only a portion of the interior of said tubular body; a firing member positioned adjacent said anvil whereby a percussion cap may be held therebetween, said firing member being slidable relative to said body to explode said cap, the portion of said interior of said body on each side of said anvil being adapted to receive explosion products from said percussion cap for passage axially through said body.

2. A toy cartridge comprising, in combination: a substantially tubular body; a closure threadably secured in one end of said body, said closure having an outwardly extending flange thereon; an opening in the end of said body remote from said closure, said opening communicating at all times with the interior of said body; a firing pin slidably positioned axially within said closure and having an enlarged head on the outer end thereof; a hammer formed on the inner end of said firing pin; a compression spring disposed about said firing pin intermediate said hammer and the inner end of said closure; and an anvil positioned transversely within said body adjacent said hammer, said anvil being substantially circular in cross section, positioned across the interior of said body and through the axis thereof thereby providing spaces intermediate said anvil and the interior surface of said tubular body.

3. A toy cartridge comprising, in combination: a substantially tubular body; a closure threadably secured in one end of said body, said closure having an outwardly extending flange thereon; an opening in the end of said body remote from said closure, said opening communicating at all times with the interior of said body; a firing pin slidably positioned axially within said closure and having an enlarged head on the outer end thereof; a hammer formed on the inner end of said firing pin; a compression spring disposed about said firing pin intermediate said hammer and the inner end of said closure; an anvil positioned transversely within said body adjacent said hammer, said anvil being substantially circular in cross section, positioned across the interior of said body and through the axis thereof thereby providing spaces intermediate said anvil and the interior surface of said tubular body; and a radially extending cap receiving flattened area formed on said anvil on the end thereof adjacent said hammer.
